UNITED STATES PATENT OFFICE.

WILLIAM A. LEFLER, OF FLINT, MICHIGAN.

WRENCH.

SPECIFICATION forming part of Letters Patent No. 767,901, dated August 16, 1904.

Application filed November 13, 1903. Serial No. 181,056. (No model.)

To all whom it may concern:

Be it known that I, WILLIAM A. LEFLER, a citizen of the United States, residing at Flint, in the county of Genesee, State of Michigan, have invented certain new and useful Improvements in Wrenches; and I do hereby declare the following to be a full, clear, and exact description of the invention, such as will enable others skilled in the art to which it appertains to make and use the same.

This invention relates to wrenches, and more particularly to that class known as "sliding-jaw" wrenches, and has for its object to provide a device of this nature which will be simple of construction and cheap of manufacture and in which the jaws may be quickly and easily adjusted.

In the drawings forming a portion of this specification, and in which like numerals of reference indicate similar parts in the several views, Figure 1 is a perspective view of the complete device. Fig. 2 is a vertical section through the sliding member of the wrench, the coöperating parts being in elevation. Fig. 3 is a view of the forward edge of the device.

Referring now to the drawings, the present invention comprises the usual stock or handle 5, having ratchet-teeth upon its forward edge and having a transverse head 7 formed upon one of its ends, one side of which forms a clamping-jaw 8. Slidably disposed upon the stock 5 is a member 9, which carries a second jaw 9'. The member 9 has the usual passage 10, with which the stock 5 is engaged, and connecting this passage 10 with the forward edge of the member 9 is a downwardly-directed diagonal slot 11. Disposed within the slot 11 is a triangular block 12, which is provided with teeth 13 upon its longest edge and lies with these teeth in engagement with the teeth 6 of the stock. To hold the block 12 in engagement with the stock, a spring 14 is provided and has one of its ends disposed in a recess 15' in the lower side of the slot 11, the remaining end of the spring bearing against the lower face 12' of the block, the ends 15

and 16 of the block projecting beyond the sides of the slot 11 and are rounded and provided with concavities in their outer faces to receive the fingers of the operator.

In adjusting the wrench the member 9 may be moved freely in the direction of the head 7; but movement in the opposite direction will be prevented by the teeth 13 engaging the teeth 6. When it is desired to move the jaw 55 in this direction, the ends 15 and 16 of the block 12 are grasped by the operator with the thumb and second finger, respectively, and the block is moved against the action of the spring 14 to disengage it from the ratchet 6, 60 when the member 9 may be moved in either direction, as desired.

In practice modifications of the specific construction shown may be made and any suitable materials and proportions may be used 65 without departing from the spirit of the invention.

What is claimed is—

1. A wrench comprising a jaw having a passage therethrough and an upwardly-directed 70 diagonal slot connecting one of its edges with the passage, said member also having a jaw projecting laterally from one of its ends, a stock having ratchet-teeth upon one of its edges slidably disposed within the passage and 75 having a laterally-projecting jaw upon one of its ends for coöperation with the first-named jaw, a toothed block slidably disposed within the slot and lying with its teeth normally in engagement with those of the stock, a spring 80 disposed within the slot and bearing against the block to hold the latter yieldably in its normal position, the ends of the block extending outwardly of the slot and adapted for engagement by the fingers of the operator to 85 move the block against the action of the spring.

2. A wrench comprising a member having a passage therethrough and an upwardly-directed slot connecting one of its edges with 90 the passage and communicating with the sides of the member, said member having a jaw pro-

jecting laterally therefrom, a stock slidably disposed within the passage, and having a laterally-projecting jaw upon one of its ends for coöperation with the first-named jaw, a block 5 slidably disposed within the diagonal slot and means for holding the block yieldably in engagement with the stock, the ends of the block being adapted for engagement by the fingers

of the operator to move it against the holding means.

In testimony whereof I affix my signature in presence of two witnesses.

WILLIAM A. LEFLER.
